UNITED STATES PATENT OFFICE.

JOHN C. NEWCOMB AND ROMEO A. CASAROTTI, OF OAKLAND, CALIFORNIA, ASSIGNEES
TO REX MANUFACTURING COMPANY, OF OAKLAND, CALIFORNIA, A CORPORATION.

BALL COCK.

Application filed August 9, 1922. Serial No. 580,622.

To all whom it may concern:

Be it known that we, JOHN C. NEWCOMB and ROMEO A. CASAROTTI, citizens of the United States, residing at Oakland, county 5 of Alameda, State of California, have invented certain new and useful Improvements in Ball Cocks; and we do declare the following to be a full, clear, and exact description of the same, reference being had to the accompanying drawings, and to the characters of reference marked thereon, which form a part of this application.

This invention relates to improvements in ball cocks of the type particularly adapted 15 to control the supply of water to tanks, especially those used in connection with water closets.

The type of ball cock shown in this invention is especially intended as an improvement 20 over the cock shown in Patent No. 1,299,708, dated April 8, 1919, to Max Harbisreitinger, the construction having been greatly simplified and the operation improved and rendered more efficient.

The principal objects of the present invention are to provide a ball-float controlled cock so constructed that the body of the same is formed of a single member; the water enters the tank from the cock in such 30 a manner that a very silent flow is had; means are provided for insuring this silence even with a high pressure of water; both the valve and its seat are easily removable without removing or dismounting the body member from the tank; and the necessary refill-tube is connected to the body in such a manner that but very little bending of the tube to suit any condition is necessary.

These objects we accomplish by means of 40 such structure and relative arrangement of parts as will fully appear by a perusal of the following specification and claim.

In the drawings similar characters of reference indicate corresponding parts in the 45 several views.

Fig. 1 is a side elevation of the improved ball-cock.

Fig. 2 is a sectional view of the same.

Referring now more particularly to the 50 characters of reference on the drawings, the numeral 1 denotes the barrel of the cock, threaded at its lower end as at 2 and provided with an integral flange 3 above the threaded portion to form a support for a 55 rubber washer 4 which rests on the bottom

of a tank, and is clamped to form a watertight joint by means of a lock nut 5 on the portion 2 which projects below the tank.

A transverse passage 6 is cut through the barrel 1 a short distance above the flange 3, 60 a water-deflecting flange 7 being formed integral with said barrel immediately above the passage 6.

The bore of the barrel from the said passage tapers outwardly therefrom to the lower 65 end of the barrel to removably receive a similarly tapered sleeve 8, the upper end is formed as a valve-seat 9 and is in substantial alinement with the lower end of the passage 6. The lower end of the sleeve has an 70 integral and outwardly projecting flange 10 which seats in a concentric but somewhat enlarged recess 11 in the lower end of the barrel, the sleeve being normally held from downward movement by the usual slip-joint 75 nut 12 employed in making the connection with the water intake-pipe leading to the cock.

Arranged to engage the seat 9 is a plunger-valve 13, of suitable material, slidable easily 80 in the bore of the barrel above the passage 6 for a short distance, the bore being enlarged from thereon up, so that the valve may be readily withdrawn when desired.

The valve 13 is attached to a stem 14 on the upper end of which is fixed a plunger 15 85 slidable in the barrel, and projecting thereabove.

Slidably mounted in a transverse slot 16 on the upper end of the plunger is a yoke 17, 90 normally held in place by a removable cap 18 on the plunger, which covers said slot, the lower ends of the yoke being connected to allow vertical movement thereof to a lever mechanism 19 mounted on the barrel, this structure being substantially as shown in the above mentioned patent. Mounted for adjustment in a vertical plane and on the outer end of the lever mechanism is the rod 20 to the outer end of which is connected the 95 usual ball-float (not shown).

Formed integral with the barrel 1 under the lever structure is a bracket or arm 21, in which is threaded an adjustment screw 22 which bears on said lever structure.

Formed integral with the barrel 1 below the plunger 15 is a tapped boss 23, to receive a street-L 24 of usual type, with a rubber washer 24^a therebetween, in which L is secured the usual form of refill-tube 25 110

which is led thence to the overflow pipe of the tank.

In operation, if the tank is empty, the valve 13 will be raised off the seat 9, allowing the water to flow into the tank, near the bottom through the passage 6. Owing to the location of this passage near the bottom of the tank, and to the influence of the deflector 7, the water will flow horizontally, and since it thus has no fall after entering the tank, the flow will be practically noiseless.

If the water pressure in the piping to the cock is very high, the screw 22 is adjusted upwardly so that the lever mechanism is raised somewhat, and the valve consequently lowered and prevented from opening to its full extent, even when the tank is empty, thus preventing too great an inrush of water and maintaining the silence of operation.

If it is desired to remove the valve 13 for replacement or otherwise, it is only necessary to disconnect the yoke 17 from the plunger 15 by removing the cap 18, when said plunger, stem 14 and valve 13, may be easily withdrawn.

If it should be necessary to renew or re-finish the valve seat owing to corrosion or otherwise, it is only necessary to remove the nut 12, the tank being empty and the water pressure being of course shut off, and start the sleeve 8 downwardly by inserting a screw-driver blade, or similar prying tool, into the recess 11 about the flange 10, and exert a bearing-down pressure upon said flange, or by downward pressure on plunger 15.

By reason of the use of the street-L in connection with the refill tube, the latter may be turned to any desired angle with but very little bending of said tube.

With the ordinary method of installing these tubes, which is by tapping them directly into the body, it very often occurs that these tubes corrode and break off just outside the body, which necessitates removing

the cock and re-tapping the tube-receiving hole therein. This is obviated with our construction, since the L member is rigid and hence may be made of a metal well able to withstand corrosion. In the event of the corrosion of the refill-tube in this case, it is only necessary to remove the L itself, and either retap it or replace it with a new one.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described our invention, what we claim as new and useful and desire to secure by Letters Patent, is:—

In a valve structure for use in liquid tanks, a tubular member having its lower end arranged to project below a tank and having an outlet to discharge into the tank, said tubular member having a straight bore from the outlet downwardly, a sleeve mounted in the straight bore of the tubular member and being bored at its lower end to receive a standard intake pipe, the upper end of the sleeve being formed as a valve-seat, and an outwardly projecting flange on the lower end of the sleeve adapted to extend across and abut against the lower end of the tubular member, whereby to locate the sleeve in the tubular member, the latter being threaded to receive a flanged nut placed about the pipe, whereby said nut will both hold the sleeve in place in the tubular member and secure the intake pipe thereto.

In testimony whereof we affix our signatures.

JOHN C. NEWCOMB.
ROMEO A. CASAROTTI.
